UNITED STATES PATENT OFFICE.

PARKE T. SNYDER, OF CHICAGO, ILLINOIS.

ELECTRICAL CONNECTOR.

1,260,085.

Specification of Letters Patent. Patented Mar. 19, 1918.

Application filed December 14, 1916. Serial No. 136,933.

To all whom it may concern:

Be it known that I, PARKE T. SNYDER, a citizen of the United States, residing at Chicago, in the county of Cook and State of Illinois, have invented certain new and useful Improvements in Electrical Connectors, of which the following is a specification.

This invention relates to improvements in electrical connectors.

- 10 Two different types of Edi-Swan lamp bases or plugs are in common use, the one utilizing a pair of contacts for two wire systems and the other a single central contact for adaptation to a single wire system.
- 15 The two systems are used quite arbitrarily by automobile manufacturers, certain cars having one wire and others two wire systems. As most of the sockets now used are constructed, it is possible to use in single
- 20 contact sockets only standard single contact lamp bases or plugs, and in double contact sockets only double contact lamp bases and plugs. The disadvantages of this lack of interchangeability to both the user and the
- 25 accessory dealer are obvious.

In my copending application Serial No. 114,880 filed August 14, 1916, for improvements in electrical connectors I have illustrated and described a form of socket adapted to receive either a single or double contact base. The present application in so far as it relates to certain of the subject matter disclosed in Figs. 6 and 7 is a continuation of the aforesaid earlier filed application.

30 One of the objects of my invention herein described is to simplify and improve the socket described and claimed in the aforesaid application.

Another object of my invention is to provide a socket with a pair of contacts arranged in position for direct engagement with the contacts of either a standard single contact base or standard double contact base.

40 A further object of my invention is to generally improve the construction of Edi-Swan type sockets, increasing their efficiency and adaptability, and also providing an improved socket in which either single or double contact bases or plugs may be used interchangeably.

Still other and further objects of the invention will become apparent to those skilled in the art from a consideration of the following description and drawings, wherein—

50 Figure 1 is a diametric sectional view through my improved double ended socket.

Fig. 2 is an end elevation of the socket shown in Fig. 1.

Fig. 3 is a transverse sectional view on the line 3—3 of Fig. 1. 60

Fig. 4 is an end elevation of a single wire plug adapted for insertion in my socket.

Fig. 5 is a diametric longitudinal sectional view of the plug shown in Fig. 4.

Fig. 6 is a diametric longitudinal sectional view through a single ended socket. 65

Fig. 7 is a transverse sectional view on the line 7—7 of Fig. 6.

Fig. 8 is a side elevation, parts of the shell being broken away, showing a single contact 70 lamp base inserted in my improved socket; and

Fig. 9 is a similar view showing a double contact lamp base inserted in my improved socket. 75

In my above referred to copending application the spring extended contacts within the socket are arranged in a manner somewhat similar to those of the socket herein described. In order, however, that one of 80 the contacts make electrical connection with the shell of the lamp base, when a single contact base is inserted in the socket, it was found necessary to add an auxiliary connection normally joining one of the contacts 85 with the wall of the socket, this connection being broken when the contact is depressed by engagement with the end of a two contact base. This expedient was found necessary because of the fact that a large portion of 90 the end of a single contact base is overlain by a frusto-conical insulator on the end of which is mounted the central single contact. In my former construction the end of one of the contacts (the one to which the auxiliary 95 connector spring is connected) is so positioned that it contacts with the base portion of the insulator on the end of a single contact base. Obviously it would be possible to construct a single contact lamp base with 100 a small insulator so that the engagement of one of the resiliently extended contacts with the metallic end of the base would not be interfered with. But lamp bases as now supplied by the manufacturers are of stand- 105 ard design and it is with the intention of providing a socket adaptable to receive either the standard single contact base or standard double contact base without the addition of auxiliary connections that the 110 present structure was evolved. If the projecting ends of one of the spring extended

connectors of my former device was bent over or flattened so as to avoid contact with the frusto-conical insulator of a single point base it is obvious, since the contact is freely 5 rotatable within its shell, that the flattened end could not be depended upon to remain in its outer position, but might rotate to a different position radially inwardly and thus engage with the insulator of a single point 10 base rather than with the metallic end portion surrounding the insulator.

With the above outlined problem before me, I have evolved the present construction in which both of the contact receiving shells 15 are of the same size, one however being positioned as near the wall of the socket shell as possible and having an eccentric opening in its head through which projects the spring extended plunger contact.

20 The eccentricity of the opening insures the end of the contact always occupying the same position and permits it to be placed sufficiently far from the axis of the shell to prevent interference with the frusto-conical insulator of a standard single contact base.

Referring more particularly to the exemplification of my invention, which I have illustrated in the drawings,

30 Figure 1 shows a double ended connector comprising a cylindrical metal shell 10 provided at its opposite ends with the usual slots 11 for receiving the locking pins of an Edi-Swan base. Midway between the 35 ends of the connector is secured a plug 12 of insulating material in which is mounted the resiliently extended contacts which engage with the contacts of the lamp base. Two diametrically opposite openings extend

40 through the plug 12 to receive the contact shells 13, 14. The shell 14 carries in its opposite end portions the outwardly extending connectors 15-15, the inner ends of which are enlarged as at 16 for sliding engagement within the shell 14, the ends of which are flanged over as at 17 to provide end abutments for the heads 18. The outer ends of the connectors 15-15 are flattened, as at 18, to provide a relatively wide contact 45 surface extending from the region adjacent the axial center of the shell 10 to a region adjacent the inner wall of the shell. A coil spring 19 is positioned within the hollow contacts and contact shell so as to resiliently 50 press the contact ends outwardly into position shown in Fig. 1.

The other contact shell 13 is positioned as close to the wall of the socket shell 10 as is possible and still leave a wall of insulating material between the socket shell and the contact shell. The end portion of shell 13 toward the axis of the socket is flanged over, as at 20, so as to position the end opening outwardly away from the axis 55 of the shell 10 thus making the axis of the

contact opening eccentric to the axis of the shell 13. Through these eccentric openings project the contact members 21, the inner ends of which are enlarged, as at 22, to fit within the shell 13. A spring 23 lies within 70 the contacts 21 and shell 13 to resiliently extend the contacts into the position shown in Fig. 1.

In Fig. 8 the numeral 50 indicates a lamp bulb mounted on a single contact Edi-Swan 75 base 51 comprising the cylindrical metal wall 52 which extends radially inwardly at its lower end forming an annular metal ring 53. At the center of the end of the base there projects a frusto-conical insulator 54 80 on the end of which is positioned the single contact member 55. The locking pin 56 engages the slot 11 and secures the base in position within the socket. The single central contact 55 of the lamp base engages the 85 resiliently extended contact 18 of the socket near its inner edge, depressing it to the position shown in Fig. 8. The other resiliently extended contact 21 engages the annular ring 53 of the base to which one of the lamp 90 filament leads is connected.

When the socket is used in connection with a two contact base or plug the circuit is made as illustrated in Fig. 9. In this view I have illustrated a lamp bulb 50^a mounted 95 on a double contact Edi-Swan base 51^a. The base comprises the cylindrical metal wall 52^a in the end of which are provided the diametrically opposite insulated contacts 57 and 58. Contact 57 engages the resiliently 100 extended contact 21 of the socket and contact 58 engages the outer portion of the resiliently extended head 18 on the contact 15 of the socket.

In Fig. 6 I have illustrated a single ended 105 socket embodying the same principle as that illustrated in Fig. 1, the lower end of the shell 10^b terminating, however, at the end of the insulating plug 12^b and being externally threaded at 25 for engagement with 110 the threaded hood 26 through the open end 27 of which extend the terminal wires 28, 29. The contact members 15 and 21 are arranged in the same manner as those illustrated in Fig. 1, being slidable within shells 115 13^b and 14^b. The lower ends, however, instead of carrying other contacts are provided with heads 30 and 31 into which lead the connecting wires 29 and 28. Binding 120 screws 32, 33 extend through openings in the insulated plug and take into threaded openings in the heads 30, 31 and bind the wires 29 and 28 in position. Apertures 34 are provided in the shell 10^b to give access to the heads of the binding screws. The threaded opening 35 in head 30 into which the screw 32 takes extends entirely through the same and registers with an opening 36 in the insulating plug which extends to the wall of the shell 10^b. The screw 32 is sufficiently 130

long so that when no wire extends into the opening in the head 30 the screw may pass entirely through the head and make electrical connection with the shell 10^b. This 5 provides for the grounding of one of the terminals of a double contact base when used in a single wire system, in which event the single wire 28 is led into the head 31 of contact 18 and screw 32 is extended 10 through head 30 into engagement with the shell 10^b, providing a ground return for terminal 21.

In Figs. 4 and 5 I have illustrated a plug adapter for connecting a single wire system 15 into either of the sockets illustrated in Figs. 1 and 6. This plug comprises an insulating base member 40 through the axial center of which extends a rod 41 having an opening in its lower end to receive the single 20 wire 42. The inner end of rod 41 serves as a center contact. A binding screw 43 takes through a side of the plug into the rod to clamp the wire in position. A metallic plate 25 44 is secured by screw 45 to the end of the insulated base 40 adjacent its periphery and is provided with an outwardly and downwardly extending lip 46 which projects slightly beyond the periphery of the base. When this plug is inserted in a socket, such 30 as shown in Fig. 1, the inner end of the rod 41 engages terminal 15 whereas the plate 44 engages terminal 21 and connects the same with the shell 10 through lip 46.

Whereas I have illustrated and described 35 but two embodiments of my invention, it will be obvious to those skilled in the art that many changes may be made therein without departing from the spirit and scope of the appended claims.

40 Having described my invention, what I claim is:—

1. An electrical connector for coöperation with either a standard double contact base, or a standard single contact base having 45 a centrally disposed insulator projecting from its end, and a contact on the top of the insulator; said connector comprising a metallic shell, an insulating body therein, a pair of independently resiliently extended contacts carried by the body, one said resiliently extended contact extending from a region near the axis of the shell to a region near the inner wall of the shell for engagement with either the center contact of 50 a single contact base or one of the contacts of a double contact base, the other resiliently extended contact being positioned diametrically opposite the first and relatively close to the inner wall of the shell for engagement with a contact of a double contact base or with the end of a single contact base at a point radially beyond the periphery of the said insulator.

55 2. An electrical connector for coöperation with either a standard double contact base,

or a standard single contact base having a centrally disposed insulator projecting from its end, a contact on the top of the insulator and an annular metal contact ring on the end of the base surrounding the insulator; 70 said connector comprising a metallic shell, an insulating body therein, a pair of independently resiliently extended contacts carried by the body, one of said resiliently extended contacts extending from a region 75 near the axis of the shell to a region near the inner wall of the shell for engagement with either the central contact of a single contact base or one of the contacts of a double contact base, the other resiliently extended contact being positioned diametrically opposite the first and relatively close to the inner wall of the shell for engagement with a contact of a double contact base or with the annular metal contact ring surrounding the insulator of a single contact base.

3. An electrical connector for coöperation with either a double contact plug or a single contact plug having a centrally disposed 90 contact with surrounding annular metallic rim insulated therefrom; said connector comprising a shell, a body part therein, a pair of independently resiliently extended contacts within the shell, one said contact 95 overlying the central portion of the shell and extending to one side thereof for engagement with either the central contact of a single contact plug or one of the contacts of a double contact plug, the other resiliently extended contact being positioned at 100 one side of the axis of the shell for engagement with a contact of a double contact plug or with the metallic rim of a single contact plug.

105 4. An electrical connector for coöperation with either a double contact base or a single contact base; said connector comprising a shell, a body part of insulating material therein, a pair of independently resiliently 110 extended contacts within the body part, one said resiliently extended contact having a disk like head extending from points near the axis of the shell to points near the inner wall of the shell, the other resiliently extended contact having its end formed eccentrically to lie in close proximity to the inner wall of the shell, and means to prevent rotation of the last said contact with respect to the body part.

115 5. An electrical connector for coöperation with either a double contact base, or a single contact base; said connector comprising a shell, a body part of insulating material therein, a pair of independently resiliently 120 extended contacts carried by the body part, one said resiliently extended contact having an end portion extending from points adjacent the axis of the shell to points adjacent the inner wall of the shell, the other 125

130

resiliently extended contact having its end formed to lie at the outer side of its axis of movement and to lie in close proximity to the inner wall of the shell at a point diametrically opposite the other resiliently extended contact.

6. An electrical connector for coöperation with either a single contact, or a double contact base; said connector comprising a metallic shell, an insulating body member within the shell, a pair of contacts carried by the body member, and wire clamping screws associated with each contact, one of said screws being arranged for engagement with its contact alone or with both its contact and the metallic shell.
7. An electrical connector for coöperation with either a single contact, or a double contact base; said connector comprising a me-

tallic shell, an insulating body member 20 within the shell, a pair of contacts carried by the body member, each said contact having a wire receiving opening therein and a threaded opening intersecting the wire receiving opening, and a binding screw engaging each threaded opening, one said screw having a length sufficient to pass entirely through its contact in the absence of a wire in its wire receiving opening and engage the metallic shell.

In testimony whereof I hereunto set my hand in the presence of two subscribing witnesses.
